SAFETY RAZOR

David Strauss, Rochester, N. Y., assignor of one-half to Julius Simon, Rochester, N. Y.

Application November 22, 1939, Serial No. 305,726

11 Claims. (Cl. 30—63)

The present invention relates generally to safety razors and more particularly to a novel combination of detachable blade, blade holder, and cap or cover plate, in which the relative arrangement and construction of these parts is such as to permit the blade to yield, in use, in the plane of its body relative to the guard of the blade holder.

It is a well known fact that the blades of safety razors of the general type wherein the blades, of single or double edge, seat on guard carrying heads for positioning between the same and overlying caps, are clamped by said caps tightly against the blade seat of the head. This is true whether or not it is intended by the cap pressure to flex or distort the blades in cutting position.

The result of all such structures is that in use, the blades are tightly clamped in position, holding the cutting edges rigidly in immovable relation to the guards throughout the shaving operation or in other words, throughout the intended use of the razor.

I have discovered that by a construction and arrangement of the corresponding parts of the razor in a manner permitting the blade to move or shift in the plane of its body on the blade seat of the head, so that its cutting edge is shiftable or yieldable toward and away from its normal effective cutting position on the guard, I am able to materially add to the comfort and effectiveness of the shaving operation, as well as considerably prolong the effective life of the blade and its cutting edge or edges. As a further consideration the invention proposes a construction and arrangement of parts which will bring about firm support of the blade on its seat and at the same time yieldingly maintain the same in a manner permitting its cutting edge to recede with respect to the guard, which construction and arrangement accommodates itself to the use of either a single or double edge blade.

For the foregoing reasons I propose a safety razor of the construction and relative arrangement of parts to be now described in reference to the accompanying drawing, which illustrates specifically the best structural mode thus far devised, for carrying the invention into practical effect.

In the drawing, which forms a part of this specification,

Figure 1 is a perspective view of the complete razor.

Figure 2 is a side view, partly in vertical longitudinal section, taken therethrough.

Figure 3 is a detail top plan view of the blade supporting head.

Figure 4 is a bottom plan view of the cap or cover plate.

Figure 5 is a detail plan view of the blade, removed, and

Figure 6 is a top plan view of a blade supporting head illustrating a slightly modified form.

Referring now to these figures and particularly to Figures 1 and 2, the handle of the razor proposed by this invention is generally indicated at 10 and may be of any convenient form and length which practice may indicate desirable. At one end the handle 10 is joined in any suitable manner to a blade supporting head or holder which is generally indicated at 11, and while in the present instance, as particularly seen in Figure 2, the holder 11 is shown integrally united to the handle, it is obvious that this connection may be of any form which may be found suitable and desirable for the purpose.

Preferably, though not necessarily, the head 11 is disposed with respect to the handle 10 at an angle inclined with respect to a right angle for greater convenience in the shaving operation and this head which is generally rectangular and provides an upper blade seat, has along its forward edge a series of teeth forming a guard 12 at opposite ends of which are undercut blade engaging stops, in line with the effective shaving position of the blade edge on the guard 12.

As far as the present invention is concerned the guard 12 and blade stops 13 may be of conventional form but in certain other respects the blade supporting head 11 embodies features peculiarly incident to the present invention. The blade 14 is plainly seen in Figure 5 and the blade holding cap 15 is plainly shown in Figure 4, the latter being employed in the present instance to hold the blade 14 on the head 11 in a novel manner to be now described.

Centrally of the head 11 there opens one end of a bore 16 extending in a direction generally lengthwise of the complete razor, at right angles to the blade supporting surface of the head 11 and through a lateral enlargement 17 of the upper portion of the handle 10, at an angle inclined with respect to the longitudinal axis of the handle. At the head end of this bore there is preferably a shallow counterbore 18 and a second and somewhat deeper counterbore 19, within the latter of which is the enlarged threaded end 20 of a stem 21. This stem extends through the bore 16 within which it is rotatable, and its opposite end projects beyond the handle ei-

largement 17 and receives a rigid knurled head or fingerpiece 22 which may be conveniently manipulated to rotate the stem 21.

The cap 15 has along its rear edge an angular flange 23 which, when the cap is placed in proper position overlying the blade 14, engages a positioning flange 24 upstanding along the rear edge of the blade supporting head 11. The flange 23 of the cap holds the rear portion of the cap away from the upper blade supporting surface of the head 11 and maintains the cap generally in an inclined position with respect to the head so that its forward edge only comes into contact with the blade and all of the remaining portion of the cap is spaced substantially from the blade in use. To preserve this relation of the parts and at the same time clamp the cap tightly in place, it is provided upon its lower surface with a hollow internally threaded boss 25 of a diameter to enter the counterbore 18 and seat against the shoulder forming the base of this counterbore. This boss receives the threaded head 20 of the stem 21 and it is obvious that upon proper rotation of the stem the cap 15 will thus be drawn snugly and firmly into the position shown in Figure 2, the engagement of the lower edge of its boss with the shouldered base of counterbore 18 limiting its movement toward the head and thus limiting the degree of pressure of the forward edge of the cap on the blade 14.

For the seating of the blade, the head 11 has rearwardly of its center upstanding and preferably rounded bosses 26 on which the blade rests rearwardly of its longitudinal center so that the blade is thus held on a slight incline with respect to the upper surface of the head substantially less, however, than the incline of the cap 15 with respect to the head, the blade when so seated, having its forward edge disposed along the guard 12 with its end portions beneath the undercut blade stops 13.

The blade is, moreover, provided at its center with an opening 14^a through which the cap boss 25 may extend or project, and this blade opening 14^a is preferably elongated in a direction transversely of the blade, to an extent that in this direction it is of substantially greater diameter than the boss whereby to permit of movement of the blade with respect to the boss in a direction transversely of the blade. Lengthwise of the blade, its opening 14^a may be just sufficient to receive the boss 25 so that the latter, extending through the blade, will prevent shifting of the blade lengthwise.

At opposite ends of the blade supporting head 11, intermediate its front and rear edges, and preferably aligned with one another and with the axis of the bore 16, are upstanding pairs of lugs 27 forming between them spaces 28. The blade 14 is provided at its opposite ends with pairs of longitudinally slotted recesses 29 forming between them longitudinal ribs 30 having outer free ends adapted to seat in the spaces 28 between the upstanding lugs 27 of the head as just previously mentioned.

Preferably the slotted recesses 29 of the blade 14 are such that the ribs 30 resulting between them are thin and flexible in the plane of the body of the blade to a degree permitting the blade, when these ribs are seated in the spaces 28 between the lugs 27 of the holder 11 to be shifted in the plane of its body between the blade supporting head 11 and the cap 15.

For the above purposes the blade is so proportioned that when initially seated on the head 75

with its longitudinal ribs between the lugs 27 its forward edge will be positioned beneath the blade stops 13 and properly aligned on the guard 12 and in thus referring to the forward edge of the blade it is to be understood that by this is meant the forward edge of the blade as placed on the head, it being obvious that this arrangement provides for the use of either a single or double edge blade.

When the blade is so placed its rear portion will rest upon the rounded bosses 26 and by a proper proportioning of the cap boss 25 which limits engagement of the forward portion of the cap with the blade to a mere contact without pressure, the blade is thus held so that in use it may shift transversely thereof to permit receding of its cutting edge with respect to the guard 12 under pressure of the elasticity of its ribs 30.

In order to permit the forward edge of the cap 15 to engage the blade 14 while creating minimum frictional resistance to the above-described movement of the blade in use, I may provide the under surface of the forward edge of the cap with a longitudinal series of recesses 31, as plainly seen in Figure 4, which will have the effect of reducing the area of contact to the extent of the proportion of these recesses to the remainder of the edge of the cap.

While some means of an elastic nature is, of course, necessary to hold the cutting edge of the blade normally in the proper cutting position with respect to the guard 12, it may be that instead of thin, flexible and elastic ribs 30 formed in connection with the blade in the manner previously described, I may utilize a blade in which these ribs are of substantially greater width and inelastic in the plane of the body of the blade. In this event the upstanding lugs 27^a of the blade supporting head 11 will be positioned to afford substantially greater spaces between them than the widths of the blade ribs, and the rearmost lugs of both pairs may have, as seen in Figure 6, angular spring members 32 anchored thereto with portions projecting into the spaces to act against the blade ribs and thus serve the same purpose, and bring about the same result, as the thin elastic blade ribs previously described.

In any event, the result of the structure as thus fully described is to maintain the blade in a manner whereby it is in use elastically held in effective shaving position and capable of yielding when facial obstructions as well as excessively tough portions of the beard are encountered. This capability I have found not only adds greatly to the comfort of the shaving operation, but considerably relieves the strains placed upon rigidly clamped blades and the relief of this strain substantially prolongs the effective life of the cutting edge of the blade.

What is claimed is:

1. A safety razor comprising a handle, a blade supporting head at one end of the handle having an upper blade supporting surface and a guard along one side thereof, a blade slidably supported on said surface and having a centrally located opening, a cover plate overlying the blade having a flange engaging the opposite edge of the head and a hollow internally threaded boss extending into engagement with a portion of the head through the opening of the blade and limiting movement of the cover plate toward the head and maintaining the plate in non-clamping relation with the blade whereby the latter is free to slidably shift on the head toward and away from the guard, a stem rotatable through a portion

of the handle and through the head having a threaded end for engagement in the threaded boss of the cover plate to clamp the latter in connection with the head, and spring means for resiliently restraining sliding movements of the blade with respect to the guard.

2. A safety razor including a substantially rectangular flat blade having a marginal longitudinally-extending cutting edge, a holder for said blade having a flat blade-supporting surface for slidably receiving the blade thereon including a guard portion adapted to underlie said edge when the blade is in position in the holder, a cover plate adapted to overlie the blade on the holder, means for clamping the cover plate lightly in contact with the blade in the holder to prevent dislodgment of the blade from the plane of said supporting surface, and cooperating means on the blade and holder for yieldingly maintaining the blade centered upon the supporting surface while permitting limited lateral displacement of the blade in its own plane relative to the cover plate and supporting surface during use of the razor.

3. A safety razor including a substantially rectangular flat blade having a marginal longitudinally-extending cutting edge, a holder for said blade having a flat blade-supporting surface for slidably receiving the blade thereon including a guard portion adapted to underlie said edge when the blade is in position in the holder, a cover plate adapted to overlie the blade on the holder, means for adjustably clamping the cover plate lightly in contact with the blade in the holder to prevent dislodgment of the blade from the plane of said supporting surface, and cooperating means on the blade and holder for yieldingly maintaining the blade centered upon the supporting surface while permitting limited lateral displacement of the blade in its own plane relative to the cover plate and supporting surface during use of the razor.

4. A safety razor including a substantially rectangular flat blade having a marginal longitudinally-extending cutting edge, a holder for said blade having a flat blade-supporting surface for slidably receiving the blade thereon including a guard portion adapted to underlie said edge when the blade is in position in the holder, retaining lugs projecting upwardly from said surface and designed for engagement with the cutting edge for determining the normal position of the blade in the holder, a cover plate adapted to overlie the blade on the holder, means for clamping the cover plate lightly in contact with the blade in the holder to prevent dislodgment of the blade from the plane of said supporting surface, and cooperating means on the blade and holder for yieldingly maintaining the blade lightly in contact with said retaining lugs while permitting limited lateral displacement of the blade in its own plane toward and away from said lugs during use of the razor.

5. A safety razor including a substantially rectangular flat blade having a marginal longitudinally-extending cutting edge, a holder for said blade having a flat blade-supporting surface for slidably receiving the blade thereon including a guard portion adapted to underlie said edge when the blade is in position in the holder, retaining lugs projecting upwardly from said surface and designed for engagement with the cutting edge for determining the normal position of the blade in the holder, a cover plate adapted to overlie the blade on the holder, means for clamping the cover plate lightly in contact with

the blade in the holder to prevent dislodgment of the blade from the plane of said supporting surface, a spring tongue on said blade capable of being displaced laterally relative to the body of the blade and in the plane thereof, and a stationary abutment on the holder designed for engagement with said tongue for maintaining the blade in position on said surface with its cutting edge bearing lightly against said lugs, said blade being capable of lateral shifting movement in its own plane relative to the cover plate and supporting surface during use of the razor.

6. A safety razor including a substantially rectangular flat blade having a marginal longitudinally-extending cutting edge, a holder for said blade having a flat blade-supporting surface for slidably receiving the blade thereon including a guard portion adapted to underlie said edge when the blade is in position in the holder, retaining lugs projecting upwardly from said surface and designed for engagement with the cutting edge for determining the normal position of the blade in the holder, a cover plate adapted to overlie the blade on the holder, means for clamping the cover plate lightly in contact with the blade in the holder to prevent dislodgment of the blade from the plane of said supporting surface, a pair of longitudinally extending oppositely directed spring tongues on said blade capable of being displaced laterally relative to the body of the blade and in the plane thereof, and a pair of stationary abutments on the holder designed for respective engagement with said tongue for maintaining the blade in position on said surface with its cutting edge bearing lightly against said lugs, said blade being capable of lateral shifting movement in its own plane relative to the cover plate and supporting surface during use of the razor.

7. A safety razor including a substantially rectangular flat blade having a marginal longitudinally-extending cutting edge, a holder for said blade having a flat blade-supporting surface for slidably receiving the blade thereon including a guard portion adapted to underlie said edge when the blade is in position in the holder, retaining lugs projecting upwardly from said surface and designed for engagement with the cutting edge for determining the normal position of the blade in the holder, a cover plate adapted to overlie the blade on the holder, means for clamping the cover plate lightly in contact with the blade in the holder to prevent dislodgment of the blade from the plane of said supporting surface, a pair of longitudinally extending oppositely directed and outwardly projecting spring tongues on said blade capable of being displaced laterally relative to the body of the blade and in the plane thereof, and a pair of stationary abutments on the holder designed for respective engagement with said tongue for maintaining the blade in position on said surface with its cutting edge bearing lightly against said lugs, said blade being capable of lateral shifting movement in its own plane relative to the cover plate and supporting surface during use of the razor.

8. A safety razor including a substantially rectangular flat blade having a marginal longitudinally-extending cutting edge, a holder for said blade having a flat blade-supporting surface for slidably receiving the blade thereon including a guard portion adapted to underlie said edge when the blade is in position in the holder, a cover plate adapted to overlie the blade on the holder, means extending through said surface

and blade for adjustably clamping the cover plate lightly in contact with the blade in the holder to prevent dislodgment of the blade from the plane of said supporting surface, and co-operating means on the blade and holder for yieldingly maintaining the blade centered upon the supporting surface while permitting limited lateral displacement of the blade in its own plane relative to the cover plate and supporting surface during use of the razor.

9. A safety razor including a substantially rectangular flat blade having a marginal longitudinally-extending cutting edge, a holder for said blade having a flat blade-supporting surface for slidably receiving the blade thereon including a guard portion adapted to underlie said edge when the blade is in position in the holder, a cover plate adapted to overlie the blade on the holder, means projecting through a portion of the handle and for adjustably clamping the cover plate lightly in contact with the blade in the holder to prevent dislodgment of the blade from the plane of said supporting surface, and cooperating means on the blade and holder for yieldingly maintaining the blade centered upon the supporting surface while permitting limited lateral displacement of the blade in its own plane relative to the cover plate and supporting surface during use of the razor.

10. A safety razor including a substantially rectangular flat blade having a marginal longitudinally-extending cutting edge, there being an inwardly extending recess in said blade at each end thereof, a flexible tongue projecting outwardly from the inner edge of each recess and contained wholly within the confines of the re-

cess, said tongues being capable of flexing movement in the plane of the blade, a holder for the blade having a flat blade-supporting surface for slidably receiving the blade thereon including a guard portion adapted to underlie the blade on the holder, a cover plate adapted to overlie the blade on the holder, means for clamping the cover plate lightly in contact with the blade in the holder to prevent dislodgment of the blade from the plane of said supporting surface, and stationary retaining abutments on said holder at opposite sides of said supporting surface adapted to receive the tongues therebetween for yieldingly maintaining the blade centered upon the supporting surface while permitting limited lateral displacement of the blade in its own plane relative to the cover plate and supporting surface during use of the razor.

11. A safety razor including a substantially rectangular flat blade having a marginal longitudinally extending cutting edge, a holder for said blade having a substantially flat blade-supporting surface for slidably receiving the blade thereon, a cover plate adapted to overlie the blade on the holder, means for clamping the cover plate lightly in contact with the blade in the holder to prevent dislodgment of the blade from the plane of said supporting surface, and co-operating means on the blade and holder for yieldingly maintaining the blade upon the supporting surface while permitting limited lateral displacement of the blade in its own plane relative to the cover plate and supporting surface during use of the razor.

DAVID STRAUSS.
